UNITED STATES PATENT OFFICE.

JOHN E. AHLVIN, OF JOLIET, ILLINOIS.

CARPENTER'S MARKING DEVICE.

1,101,516.

Specification of Letters Patent. Patented June 30, 1914.

Application filed June 14, 1913. Serial No. 773,770.

To all whom it may concern:

Be it known that I, JOHN E. AHLVIN, a citizen of the United States, residing at Joliet, in the county of Will and State of Illinois, have invented a new and useful Improvement in Carpenters' Marking Devices, of which the following is a specification.

This invention relates particularly to 10 means for marking door-jams and doors to facilitate the attachment of hinges; and the primary object of the invention is to provide a simple and inexpensive marking-device which will enable the hinges to be located with facility and accuracy.

The invention is illustrated in the accompanying drawing, in which—

Figure 1 represents a sectional view of a door-jamb or casement; Fig. 2, a front elevational view of the improved marking-implement; Fig. 3, an edge view of the door; Fig. 4, a perspective view of a stop or abutment employed; Fig. 5, a perspective view of an adjustable marker employed; Fig. 6, 25 a perspective view of a companion marker; and Fig. 7, a section on an enlarged scale taken as indicated at line 7 of Fig. 2.

In the drawing, A represents a door-jamb or casement; B, a door; and C, my improved marking-device adapted to serve in marking the hinge-locations for the door and door-jamb.

The marking-device C comprises a rod or bar 1, a stop or abutment 2 applied to the 35 upper end thereof; and pairs of adjustably-mounted markers or blades 3 and 4. The bar or mounting 1 may be of hard wood, if desired. It preferably has one beveled edge, as indicated at 1^a. The abutment 2 preferably comprises a stamping comprising a vertical wall 2^a, a vertical wall or edge-flange 2^b which is oblique to the wall 2^a, a vertical wall or edge-flange 2^c which is perpendicular to the wall 2^a, and a flange 2^d 45 which is turned outwardly at right angles to the upper edge of the wall 2^a. The edge-flange 2^b corresponds with the beveled edge 1^a of the rod, and a set-screw 5, extending through the flange 2^d, serves as a means for 50 clamping the member 2 in position. The member 3 comprises the vertical wall 3^a, the oblique vertical wall or edge-flange 3^b, the edge-flange 3^c, and the horizontal chisel-edge 3^d, which is preferably formed by striking the metal of the wall 3^a outwardly and

sharpening it, with the bevel down. The member 4 comprises the vertical wall 4^a, the oblique vertical edge-flange 4^b, the edge-flange 4^c, and the horizontal chisel-edge 4^d. In this case, the bevel of the chisel-edge is 60 up. Set-screws 5 are employed in connection with the members 3 and 4.

In the illustration given, three pairs of markers are shown, corresponding with three hinges of a door.

The rod or bar 1 is of suitable length to fit within the door-opening at 6, adjacent the stop 7, the upper surface of the flange 2^d bearing against the upper member of the door jamb. The members 3 and 4 of each 70 pair of markers are adjusted to correspond with the length of the hinge; and assuming the implement to be entered in the door-opening and disposed adjacent the stop 7, with the chisel-edges against the vertical 75 member of the door-jamb, the marking may be effected by tapping upon the opposite side of the bar 1 in the vicinity of the markers. The door may be correspondingly marked, by engaging the flange 2^d over the 80 upper edge of the door, so that the chisel edges will bear against the rear edge of the door by tapping the bar at the locations where the markers are, so that the exact locations of the hinges may be indicated on 85 the door. The marks on the door-jamb are indicated at 8; and the marks on the door are indicated at 9. The thickness of the flange 2^d will give a desirable clearance at 90 the upper edge of the door. It will be understood, of course, that the chisel-edges are square to the rod or bar 1, so that the marks made on the door and door-jamb will afford an accurate guide for the chisel in the hands of the carpenter when these parts are 95 to be mortised to receive the hinges.

By employing for the abutment 2^d, and the chisel-edges 3^d and 4^d which are open at one side, and set-screws for clamping the members in place, any desired adjustment 100 may be readily effected. Moreover, the members may be readily removed from one bar and applied to another to correspond with a door of any height. Again the bar carrying the adjustably-secured members 105 may be replaced as often as will be necessary.

The foregoing detailed description has been given for clearness of understanding, and no unnecessary limitation should be understood therefrom, but the appended 110

claims should be construed as broadly as permissible in view of the prior art.

What I regard as new and desire to secure by Letters Patent is—

- 5 1. In a marking device of the character set forth, the combination with a bar having a beveled edge, of adjustably mounted marking members adapted to slidably embrace said bar, each of said members comprising
- 10 a front wall having a portion thereof struck outwardly, said latter portion being sharpened to form a marking blade, and rearwardly extending side walls one of which is inclined inwardly toward the opposing wall and adapted to contact with the beveled edge of the bar, and clamping means
- 15

coöperating with said side walls to secure the marking member to the bar.

2. As an article of manufacture a marking device comprising a front wall having a portion thereof struck outwardly, said latter portion being sharpened to form a marking blade, and rearwardly extending side walls one of which is inclined inwardly toward the opposing wall, and clamping means coöperating with said side walls to secure said marking member in adjusted marking position.

JOHN E. AHLVIN.
